US0D1035381S

(12) **United States Design Patent** (10) **Patent No.:** **US D1,035,381 S**
(45) **Date of Patent:** **** Jul. 16, 2024**

(54) **ROLLING GRILLING BASKET**

(71) Applicant: **Shenzhen Haipin Yigou Trading Co., Ltd.**, Shenzhen (CN)

(72) Inventor: **Zhiqiang Tang**, Hunan (CN)

(73) Assignee: **Shenzhen Haipin Yigou Trading Co., Ltd.**, Shenzhen (CN)

(**) Term: **15 Years**

(21) Appl. No.: **29/877,409**

(22) Filed: **Jun. 6, 2023**

(51) LOC (14) Cl. **07-02**

(52) U.S. Cl.

USPC **D7/409; D7/354**
